UNITED STATES PATENT OFFICE.

JOHN L. CREVELING, OF NEW YORK, N. Y.

DESIGN FOR A REFLECTOR.

SPECIFICATION forming part of Design No. 29,471, dated October 11, 1898.

Application filed September 10, 1898. Serial No. 690,697. Term of patent 14 years.

To all whom it may concern:

Be it known that I, JOHN L. CREVELING, of New York, in the county of New York, State of New York, have invented and produced 5 a new and original Design for Reflectors for Gas-Lamps, of which the following is a complete specification, reference being had to the accompanying drawings.

My invention comprehends a new and original design for reflectors for gas-lamps.

Figure I is a perspective view of one of my cup-reflectors, looking toward the lower end thereof. Fig. II is a central vertical longitudinal section of the same.

15 As shown in the drawings, the leading or material feature of my design consists of a

reflector having a cup-shaped body part 1, and near its open end a pair of fillets 2 and 3, defining between them a groove 4.

5, 6, and 7 indicate openings in the bottom 20 of the reflector.

Having described my invention, what I claim, and desire to secure by Letters Patent, is—

The design for a reflector as herein shown 25 and described.

In testimony of all which I have hereunto subscribed my name.

JOHN L. CREVELING.

Witnesses:

H. G. DARWIN,
ELMER E. ALLBEE.
